CLAIM

The ornamental design for a mobile phone case, as shown and described.

DESCRIPTION

FIG. 1 is a top-front perspective view of a mobile phone case showing my new design;

FIG. 2 is a bottom-front perspective view thereof;

FIG. 3 is a top-rear perspective view thereof;

FIG. 4 is a bottom-rear perspective view thereof;

FIG. 5 is a front elevational view thereof;

FIG. 6 is a rear elevational view thereof;

FIG. 7 is a left elevational view thereof;

FIG. 8 is a right elevational view thereof;

FIG. 9 is a top plan view thereof; and,

FIG. 10 is a bottom plan view thereof.

In FIGS. 1–10, the broken lines depict an unclaimed mobile phone. In FIGS. 3–4, and 6, the broken lines depict an unclaimed plurality of elevating protrusions. The broken lines form no part of the claimed design.
